EUGEN MANDLER, OF VIENNA, AUSTRIA, ASSIGNOR TO THE FIRM CLIMAX MOTOR-
ENWERKE UND SCHIFFSWERFT LINZ A. G., OF VIENNA, AUSTRIA

CYLINDER OF INTERNAL-COMBUSTION ENGINES

Application filed January 30, 1929, Serial No. 336,239, and in Austria November 7, 1928.

My invention relates to a cylinder for internal combustion engines especially for two-stroke cycle engines with the crank case used as a scavenging pump. In such engines the cylinder cooling jacket is commonly provided, as shown in Figure 4 of the accompanying drawing, so as to run parallel with the cylinder wall and to terminate at the lower end of the cylinder, the wall of the crank case extending from there obliquely outwards and downwards. In this case, only the cylinder can be cooled, whereas the cooling of the crank case cannot be obtained, this cooling being very important for the suction work of the engine, since the crank case serves as an air pump. Furthermore in the structure above given, the joint surfaces of the various openings on the side walls, such as cleaning holes, air inlets and exhaust opening, are situated in different planes so that said surfaces have to be machined separately. Furthermore, the bevelled surface of the cylinder requires a relatively large amount of work in treating or finishing it, for example in painting it. The main object of my invention, therefore, is to avoid the above drawbacks by forming the cylinder cooling jacket by rectilinear generatrices running from the periphery of the upper cylinder flange tangentially to the outline of the crank case. By this means a very effective cooling of the upper portion of the crank case as well as of the scavenging air channel and the air inlets, will be obtained, as the cooling space extends further downwards. The substantially rectilinear surface of the cylinder, obtained by this arrangement, enables the several joint surfaces located on the sides of the cylinder to be simultaneously tooled or finished, so as to effect a considerable reduction of the cost of production.

Further objects of my invention will appear from the following detailed description.

In Figures 1, 2 and 3 of the accompanying drawings one form of construction of the present invention is represented by way of example. Figs. 1 and 2 show a cylinder formed according to the invention, in longitudinal and cross section. Fig. 3 is a horizontal section through 3—3 in Fig. 2. Fig. 4

represents a cross section through a cylinder of the usual form.

According to Fig. 4, the cylinder cooling jacket *m* is parallel to the cylinder wall *n* and terminates at the lower end *o* of the cylinder. In contrast thereto, the cooling jacket according to the present invention (Figs. 1, 2 and 3) extends rectilinearly from the periphery of the upper cylinder flange *p* to the outline of the crank case. By this means a cooling space *g* is formed above the crank case, representing four water pockets *h* extending downwards in the corners of the crank case. It will be seen that by the said pockets *h* a very effective cooling of the air inlets *b* is obtained. Furthermore the scavenging air channel *d* is surrounded by the cooling water not only on its narrow lateral faces, but also on its rear side *e*. The joint surfaces of the cleaning holes *c*, the air inlets *b* and the exhaust opening *r* are situated in common planes so as to be simultaneously tooled or finished in one working stroke of the machine tool.

It is desirable to have a free downward excess of stroke of the tools machining the above-mentioned joint surfaces. Such a free excess of stroke is usually prevented by the forwardly projecting connecting flanges *i* (Fig. 4). It is further an object of the invention to provide the connecting flanges *i* of the cylinder within the limits of the two planes containing the above-mentioned joint surfaces, so that the tools working these surfaces, for example planing tools, milling cutters or grinding wheels, have a free downward excess of stroke.

In addition to the advantages above indicated a considerable enlargement of the cooling space is obtained without increasing the main dimensions of the cylinder, and furthermore, as shown by a comparison between Figs. 2 and 4, a strong and pleasing form, capable of resisting vibrations.

The cooling-water pipes are usually connected to a flange on the cylinder, such as *k*, Fig. 4, and located outside the cylinder. Such pipes impair the usefulness of the engine and are exposed to damages. They are therefore avoided according to the pres-

ent invention, a further object of the invention being to provide one or more channels *k*' forming downward extensions of the cooling space, running within the walls of the crank case and opening into the base surface of the upper part of the crank case which is in one piece with the cylinder, where the connection with the corresponding feed pipes is made.

10 It is obvious that the present invention is applicable to single-cylinder engines as well as to multi-cylinder engines.

What I claim is:

15 1. An internal combustion engine working on the two stroke cycle comprising in combination a cylinder, a crank case having an upper part in one piece with the cylinder, the said crank case being intended to be used as a scavenging pump, air inlets in the crank case, a cylinder cooling jacket having water pockets extending downwards in the corners of the crank case to cool the said air inlets, and a water inlet channel in open communication with one of the said water pockets and extending to the base of the said upper part of the crank case.

20 2. An internal combustion engine working on the two stroke cycle comprising in combination a cylinder, a crank case having its upper part in one piece with the cylinder and the said crank case being intended to be used as a scavenging pump, a cylinder cooling jacket having an outer wall bounded by a surface generated by a straight line running from the upper cylinder edge tangentially to the outline of the crank case and moving round the cylinder, an air inlet in said crank case, an exhaust passage extending from the cylinder to the bounding surface of the cooling jacket, cleaning holes in the outer wall of said jacket and machined joint surfaces in the said wall surrounding the end of the exhaust passage therein, said air inlet and said cleaning holes, said machined surfaces lying in common planes, and connecting flanges located within the space bounded by these planes.

25 3. An internal combustion engine working on the two stroke cycle principle including a cylinder, a crank case adapted to be used as a scavenging pump, a scavenging air channel, a jacket for a cooling medium enclosing the cylinder, back and sides of the scavenging air channel and the upper part 30 of the crank case, the outer surface of the cooling jacket being formed by straight lined generatrices running from the upper cylinder edge tangentially to the outline of the crank case.

40 4. An internal combustion engine working on the two stroke cycle principle including a cylinder, a crank case adapted to be used as a scavenging pump, a scavenging air channel, said crank case having air inlet openings therein, and a jacket for cooling me-

dium extending about the upper part of the crank case and the air inlets therein and the cylinder and back and sides of the scavenging air channel, the outer surface of the cooling jacket being formed by straight lined generatrices extending from the upper cylinder edge tangentially to the outline of the crank case, said jacket being provided with water pockets extending downwardly to the corners of the crank case.

75 In testimony whereof I have signed my name to this specification.

EUGEN MANDLER.
